UNITED STATES PATENT OFFICE.

BERTRAM PARROTT GRAY, OF SUTTON COLDFIELD, ENGLAND.

ANTISLIP DEVICE FOR HORSESHOES.

1,419,251.

Specification of Letters Patent. Patented June 13, 1922.

Application filed January 24, 1920. Serial No. 353,782.

To all whom it may concern:

Be it known that I, BERTRAM PARROTT GRAY, a subject of His Majesty The King of Great Britain and Ireland, residing at 5 Ellangowan, Bishops Road, Sutton Coldfield, England, have invented new and useful Improvements in Antislip Devices for Horseshoes, of which the following is a specification.

10 This invention has reference to improved anti-slip devices for horseshoes.

According to my invention a steel roughing piece of inverted U-shape in cross-section is provided and adapted to be placed 15 between the sides of the shoe to bear against the under side of the frog, or against the under side of the hoof at or near the toe, with its two flanges or roughs crosswise of the shoe; and this roughing bar has two 20 thin side wings preferably made separately from the U-shaped roughing pieces as a thin flat section resilient cross-bar which passes through and fits in the channel underneath the web of the inverted channel section 25 roughing piece and projects beyond the same to form the said two side wings which fit on the top of the shoe to which they are secured before the shoe is nailed on the hoof. Or as a modification the side wings may be 30 made integral with the channel section roughing piece.

By the two flanges or roughs of the roughing piece coming into contact with the road crosswise of the shoe, an efficient grip is 35 obtained to prevent slipping. The said inverted channel between the two flanges or roughs may, if desired, be filled in with indiarubber or rope or other suitable material.

40 In order to form a proper level bearing for the frog on the top of the roughing piece, I may provide a covering strip of thin sheet-metal which covers the same and the resilient cross-bar and is preferably fixed 45 to the latter by any convenient means, as by cross bands of thin metal which embrace the covering strip of the cross-bar.

Or as a modification the central portion 50 of the resilient cross-bar may be rebated or set down for a distance equal to the thickness of the web of the roughing piece so that the top of the latter will be about flush with the top of the cross-bar.

55 My invention is illustrated by the accompanying drawings, of which—

Figure 1 is a longitudinal sectional eleva-

tion of a horseshoe with my roughing device applied thereto;

Fig. 2 is a plan of the same;

Fig. 3 is a rear elevation of the same; 60

Fig. 4 shows the resilient cross-bar and steel roughing piece detached from the shoe;

Fig. 5 is a plan of the resilient cross-bar separately;

Fig. 5^x is a perspective view of a slightly 65 modified form of the roughing piece;

Fig. 6 is a back elevation of a modified form of the combined U-shaped roughing piece and its side wings constructed in one 70 piece;

Fig. 7 is a plan of the same;

Fig. 8 is an end view of the same;

Fig. 9 is a rear elevation of a further 75 modification of the combined roughing piece and its resilient cross-bar furnished with a thin sheet-metal covering bar;

Fig. 10 is a plan of the same;

Fig. 11 is a cross-section of the same;

Fig. 12 is a sectional back elevation of a 80 further modified form of the roughing piece and its resilient cross-bar;

Fig. 13 is a rear elevation of the resilient cross-bar shown in Fig. 12 separately; and

Fig. 14 is a plan of the same.

A is the U-shaped steel roughing piece, 85 and this is situated between the sides of the shoe B preferably at the back part thereof as shown, and C is the thin flat section resilient cross-bar which forms the two side wings and which passes through and fits in 90 the channel underneath the web 1 and between the two side flanges 2 of the roughing piece A and also projects far enough at each side of the same to fit on to the top of the heel parts of the shoe to which the said cross-bar C is secured by any convenient means, as by the head parts of horseshoe nails passing through holes 3 in the cross-bar C and through corresponding holes in the shoe and clinched over if necessary on the under side 100 of the shoe. Or other suitable means may be provided for securing the resilient cross-bar C to the shoe.

When the shoe is in use the frog bears on 105 the upper surface of the web of the roughing piece A, and by the two flanges or roughs 2 coming into contact with the road, an efficient grip is formed to prevent slipping. The flat section resilient cross-bar C is preferably made with a gap 4 at each side, the 110 terminations 5 of which form rebates or shoulders against which the sides of the

roughing piece A bear and by which said roughing piece is prevented from moving longitudinally of the cross-bar C.

If the frog is not low enough for the upper face of the web of the roughing piece A to bear against it, then this space can be made up with indiarubber or other suitable material fixed in between the top surface of the roughing piece and the under side of

10 the frog.

If desired as a modification, as shown for instance in Figs. 6, 7, and 8, the roughing piece and resilient cross bar may be made as an integral member having two side wings 15 C^1 , C^2 , but the latter in this case must be reduced in thickness by forging or other suitable means so as to fit on to the top of the shoe and project but very little above the upper surface of the same.

20 As a further modification a strip or piece of leather or other suitable material may be substituted for the resilient cross-bar C and may be arranged to pass through the roughing piece A as above described and be fixed 25 to the top surface of the shoe under the hoof by rivets or other suitable means, and may also be fixed to the web 1 of the roughing piece A by rivets or other suitable means, as will readily be understood.

30 Two or more of the said roughing pieces A combined with their cross-bars C or side wings may if desired be used with one and the same shoe and arranged say one at the heel and the other near the toe and with or 35 without a third roughing piece or cross-bar in an intermediate position, or in some cases the intermediate one may be used without the others or with only one of them, as will readily be understood.

40 In order to afford a comparatively proper level bearing for the frog on the top surface of the resilient cross-bar, I may provide on the top of the roughing piece A and its resilient cross-bar C a covering strip D (see 45 Figs. 9, 10 and 11) of thin sheet-metal which covers the same and is preferably fixed to the resilient cross-bar C by any convenient means, as by cross bands E of thin metal which embrace the covering strip and the 50 cross-bar. The nail heads or other means which secure the cross-bar to the horseshoe also pass through corresponding holes in the covering strip.

Or as a further modification of my inven-

tion (see Figs. 12, 13 and 14) the central portion 6 of the resilient cross-bar is rebated or depressed for a distance equal to the thickness of the web 1 of the roughing bar A, this rebated part being of about the same width as the roughing bar so that the top of the latter will fit therein and be about flush with the top of the cross-bar C.

Or as a further modification, the side parts 7 and 8 may be extended and thinned down by pressure as in Fig. 5^x so as to avoid the two sudden steps that there otherwise might be between the level of the roughing piece A and the top of the resilient cross-bar C.

What I claim as my invention and desire to secure by Letters Patent is:—

1. A device of the class described, comprising a member having a web portion and a pair of rigid flanges projecting at right angles thereto, and means for securing said member to a horseshoe, whereby the web portion is in position to abut against the frog of a horse's hoof and the flanges extend transversely of the shoe between the sides thereof for engaging the road with their longitudinal edges.

2. A device of the class described, comprising a rigid U-shaped member, and a resilient member fitting between the flanges of said U-shaped member and adapted to be secured at its ends to a horseshoe, whereby the U-shaped member extends transversely of the shoe with its web in position to abut the frog of a horse's hoof and its flanges extending transversely of the shoe, for engaging the road with their longitudinal edges.

3. A device of the class described, comprising a rigid U-shaped member, a resilient member fitting between the flanges of said U-shaped member and adapted to be secured at its ends to a horseshoe, so that the U-shaped member extends transversely of the shoe with its web in position to abut the frog of a horse's hoof and its flanges extending transversely of the shoe, for engaging the road with their longitudinal edges, and means for maintaining said members against longitudinal movement one relatively to the other.

In testimony whereof I have signed my name to this specification.

BERTRAM PARROTT GRAY.
